United States Patent Office

Des. 215,905
Patented Nov. 4, 1969

215,905

ENDOSCOPE

John E. Hotchkiss, Corte Madera, Calif., assignor to
Hotchkiss Instruments, Inc., a corporation of
California

Filed Aug. 27, 1968, Ser. No. 13,292

Term of patent 14 years

Int. Cl. D24—02

U.S. Cl. D83—12

FIG. 3

FIG. 2

FIG. 1

FIG. 6

FIG. 4

FIG. 5

FIGURE 1 is a front elevation of the endoscope;
FIGURE 2 is a rear elevation thereof;
FIGURE 3 is a top plan view thereof;
FIGURE 4 is a left end view thereof;
FIGURE 5 is a right end view thereof; and
FIGURE 6 is a bottom plan view thereof.
The dominant features of my design reside in the portions shown in full lines.

I claim:

The ornamental design for an endoscope, as shown and described.
